WEB GUIDING APPARATUS

Claude A. Hogan, Cedartown, Ga., assignor, by
mesne assignments, to The Goodyear Tire &
Rubber Company, a corporation of Ohio

Application September 6, 1951, Serial No. 245,399

2 Claims. (Cl. 242—76)

1

The present invention relates to an improved apparatus for producing a generally cylindrical web package. More particularly, the invention pertains to a means for unwinding a web, fabric, film, or the like of uniform lateral dimension and of substantially continuous length from a package, and rewinding the material to form a uniform cylindrical package free from axial offsetting of the marginal edges of the web as it is rewound.

In conventional fabric mill operations, for instance, it is frequently necessary to unwind and subsequently rewind the fabric rolls or packages as they come from the looms on which they are woven. One such instance is found in the procedure of the inspection and repair of the fabric. It is necessary to remove the fabric completely from its original package in order to run it over an inspection table, after which it must be rewound substantially in the form of the original package. After inspection and repair, the fabric is customarily unwound again, passed through a brusher to remove loose threads, fibers, and other extraneous material which the fabric may have picked up in the course of its handling and finally rewound into a package for shipment.

By virtue of this continual rebuilding of the package, shifting or axial offsetting of the fabric in its lateral dimension is frequently introduced, thereby creating a final package which is not truly cylindrical and thus is very difficult to handle. This difficulty of handling is most pronounced if the package is to be wrapped for shipping to another mill for further use or treatment. Thus, it is important in forming the final package to have a bundle which is generally cylindrical.

The apparatus of the present invention is particularly advantageously adapted to produce this desired result. The term "web," as employed hereinafter, is intended to cover films, fabrics, and other like materials broadly, whether woven, calendered, laminated, or cast, as long as they are of a generally uniform lateral dimension and of substantial length.

It is, therefore, an object of the present invention to provide an apparatus for producing a web package which is of uniform cylindrical shape and free from offsetting or shifting in a direction parallel to the axis of the cylinder or the lateral dimension of the web.

It is a further object of the present invention to provide a web packaging apparatus having all of the above-mentioned attributes and being ca-

10 pable of use in combination with either conventional inspection equipment or brusher apparatus or the like.

Other important objects and advantages will 15 become apparent as the following description of one form of web packaging apparatus embodying the principles of the present invention proceeds.

In the drawings, Fig. 1 represents a plan view 20 of a web packaging apparatus with parts broken away and portions thereof shown diagrammatically. Fig. 2 is an end elevation of the web packaging apparatus with parts in section and at a somewhat larger scale. Fig. 3 is a partial elevation of the apparatus of Fig. 1 as seen from the line 3—3 therein at a scale corresponding to that of Fig. 2. Fig. 4 is an enlarged detail of a portion of the apparatus as seen from the line 4—4 in Fig. 2. Fig. 5 is an enlarged section taken along the line 5—5 in Fig. 1.

In the drawings, the reference numeral 1 identifies the web packaging apparatus generally. The web packaging apparatus 1, as shown in Fig. 1, embodies a supply package 2 and a wind-up package 3 from one to the other of which a web 4 is transferred. In the course of its transfer from the supply package 2 to the wind-up package 3, the web 4 is passed through some form of conventional equipment such, for example, as the brusher unit 5.

As previously explained, the web 4 is essentially a material having a uniform lateral dimension defined by the edges 6 and 7 thereof and being of indeterminate length. When such material as the web 4 is transferred from a supply package 3 to a wind-up package 4, the edge 6 or 7 is frequently caused to shift in an axial direction as the wind-up package is built up. As a result of this lateral shifting or axial offsetting, as it is sometimes referred to, the wind-up package 3 will not be truly cylindrical in shape. Oftentimes the ends of the package will project or indent from the ends of the support upon which they are wound to an extent such that they are very difficult to process in subsequent handling.

The supply package 2, as it comes from the loom or other fabricating apparatus upon which it is formed or through which it has previously been passed, is customarily supported upon a wooden core 8. This wooden core 8 is provided with a removable shaft 9 which extends axially of the wooden core. The supply package 2, with its wooden core 8 and shaft 9, is transported on a dolly (not shown) and shifted in a manner

3

hereinafter described to the carriage 10 of the web packaging apparatus 1.

The carriage 10 embodies a frame structure 11 which comprises a pair of lower channel members 12 to the inner surface of which a number of vertical supports 13 are secured as by welding. The vertical supports 13 carry at their uppermost ends a pair of cross members or I-beams 14 which are disposed in generally parallel relation to the lower channel members 12. The I-beams 14 are provided with portions projecting at one end thereof somewhat beyond the over-all width of the carriage 10 for the purpose of facilitating the transfer of the supply package 2 from its dolly to its eventual portion in the carriage.

Each of the I-beams 14 is provided with a cradle 15 for the reception of the bearing portion 16 of the shaft 9 which supports the wooden core 8 on which the supply package 2 is wound. The channel members 12 are mounted on rollers 17 carried in the brackets 18 which are secured to the channel members. The rollers 17 render the carriage 10 capable of shiftable movement in a direction generally parallel to the lateral dimension of the web 4 of the axis of the supply package 2 as it is supported between the cradles 15 on the I-beams 14. The rollers 17 are mounted in the tracks or guides 19 which serve to insure that the carriage 10 will move only in the desired direction.

Between the rollers 17 and extending transversely of the channel members 12 in the carriage 10 are the transverse members 20 which may take the form of I-beams. These transverse members 20 are suspended below the channel members 12 as by means of the attaching members 21. The transverse members 20 serve to provide a rigid support for the ends of the carriage 10, each of which comprises one of the cross members 14, one of the channel members 12, and a pair of the vertical supports 13.

An end of the web 4 is withdrawn from the supply package 2 and is passed over a series of guide bars 22, 23, and 24 which are mounted in the support bracket 25 secured to the wall of the brusher unit 5. These guide bars 22, 23, and 24 serve to introduce a slight tension in the web 4 and maintain the proper widthwise relation of the edges 6 and 7 of the web 4 preparatory to its entering the brusher unit 5. The web 4 is next passed around the roll 26 rotatably supported on the brusher unit 5 as by means of a pair of bearing mountings 27.

After passing through the brusher unit 5, the web 4 is passed to the wind-up unit identified generally by the reference numeral 28. The supporting of the wind-up package 3 in the wind-up unit 28 is accomplished in much the same manner as that previously described in connection with the carriage 10. The wooden core 29 is provided for the building up of the wind-up package 3 and is supported by a shaft 30 cradled in a pair of stationary vertical supports 31. The wind-up package 3 is positively rotated by a suitable drive mechanism 32 or other convenient source of power associated with the unit through which the web 4 is passed in its path of travel from the supply package 2 to the wind-up package 3.

As the web 4 passes between the supply package 2 and the wind-up package 3, its edge 6 contacts the feeler element 33 (see Fig. 4). The feeler element 33 has a guide portion 34 of notched or V-shaped form for the reception therein of the edge 6 of the web 4. The feeler

element 33 forms a part of the mercury switch 35 and serves to actuate the switch whenever the edge 6 of the fabric web 4 shifts laterally, permitting the feeler element in contact therewith to move about its pivotal mounting. The mercury switch 35 is supported by means of the bracket 36 affixed to the brusher unit 5 so that the feeler element 33 thereof will be in constant contact with the edge 6 of the traveling web 4.

The mercury switch 35, under the action initiated by the feeler element 33, controls the operation of a prime mover or motor 37. The motor 37 is equipped with a drive shaft 38 supported at its outermost end in a bearing mounting 39. The worm gear 40 on the drive shaft 38 meshes with the gear 41 which is secured to a stub shaft 42. The gear 41 drives the stub shaft 42 and in turn actuates the sprocket 43 keyed to the stub shaft as by means of the feather 44. The entire gearing arrangement just described is enclosed in a suitable cover 45.

The sprocket 43 serves to drive a sprocket 46 mounted on a suitable bearing mounting 47 secured to the floor between the guides 19 in the manner shown in Fig. 2. This driving relationship is accomplished by means of the chain 48. In order to effect lateral shifting of the carriage 10 in the guides 19, one of the links 49 of the chain 48 is secured to the web portion 50 of one 30 of the transverse members 20 as by means of a bolt 51 secured thereto as by means of the nut 52, all of which is illustrated in greater detail in Fig. 5 of the drawing.

In order to prevent overrunning of the motor 37 whenever the current which energizes it is cut off as, for example, by the actuation of the mercury switch 35 to a neutral position, the motor brake 53 is provided for the purpose of stopping the rotation of the drive shaft 28. When the motor brake 53 is operated, it prevents the shaft 38 from rotating and insures a quick stoppage of the actuation of the gear 41 and the chain and sprocket drive embodying the sprockets 43 and 46 connected by the chain 48. Other similar precautions and safety features may be incorporated to control the apparatus. All such devices may be of conventional design and thus form no part of the present invention.

A pair of cam elements 54 and 55 are mounted on one of the guides 19 as shown in Fig. 3 of the drawings. These cam elements 54 and 55 serve to prevent overtravel by limiting the shiftable movement of the carriage 10 over a relatively short distance equal to the spacing provided between the said cam elements. A pair of limit switches 56 and 57 are suitably mounted upon a bracket 58 supported by the flange portion of that one of the transverse members 20 which is adjacent the positions of the cam elements 54 and 55. The limit switches 56 and 57 have trip levers 59 and 60, respectively, which are so positioned that they will be flipped upon contact with the cam element 54 or 55, as the case may be, depending upon which end of the guides 19 the carriage 10 is approaching in its lateral movement. The actuation of either of the limit switches 56 and 57 will effectively deenergize the entire apparatus so as to provide a factor of safety in its operation.

As the supply package 2 diminishes in its circumference to a point where the end of the web 4 thereon will pass through the brusher unit 5, it is desirable to halt the further operation of the web packaging apparatus 1 and thereafter to control its operation manually. This is accom-

plished by means of an assembly identified generally by the reference numeral 61.

The assembly 61 embodies a lever arm 62 which extends vertically and substantially perpendicular to the transverse members 20. A roller 63 secured to the uppermost end of the assembly 61 by means of the pin 64 and the nut 65 contacts the outer periphery of the supply package 2 as it is rotated by the removal of the web 4 therefrom. The lever arm 62 has a boss 66 at its lowermost end through which a pin 67 extends for securing the lever arm in the desired relationship with respect to the axis of the horizontally disposed shaft 68 of the assembly 61.

The shaft 68 is supported in a position projecting outwardly from the channel member 12 at one end of the carriage 10 as by means of the brackets 69, 70, and 71 in such fashion that it will rotate about its longitudinal axis. Bracket 69 is supported by one of the transverse members 20, while the brackets 70 and 71 are secured to the channel member 12. A handle 72 is provided at the end of the shaft 68 opposite that to which the lever arm 62 is secured.

The handle 12 facilitates the manual operation and control of the web packaging apparatus 1 after the supply package 2 has diminished to a predetermined minimum size in a manner to be described in greater detail hereinafter. In addition, the handle 12 which is secured to the shaft 68 by means of a set screw 73 serves as a counterweight maintaining a predetermined torque upon the shaft and keeping the roller 63 on the lever arm 62 in contact with the supply package 2. A spiral spring 74 extending about a portion of the shaft and securely anchored at one end thereof in a collar 75 which is keyed to the shaft and at the other in the collar portion 76 of the support 69 also serves the same purpose.

A second collar member 77 is secured to the shaft 68 intermediate the collar 75 and the handle 72. This collar member 77 has a finger 78 projecting downwardly therefrom. The finger 78 is adapted to contact the trip lever 79 forming part of a microswitch 80 which is mounted on one of the upwardly projecting flanges of one of the channel members 12. Thus, as the lever arm 62 of the assembly 61 moves in the direction indicated by the arrow in Fig. 2 of the drawings with the diminution of the supply package 2, it will cause the shaft 68 to rotate. As the shaft 68 rotates, simultaneously causing the rotation of the collar member 77, the finger 78 in contact with the trip lever 79 of the switch 80 will eventually release the trip lever.

When this occurs, the switch 80 breaks the circuit controlling the drive mechanism 32 operating the wind-up unit 28 of the web packaging apparatus. It is thereafter necessary to control the operation of the drive mechanism 32 by the manual shifting of the handle 72 in such fashion that the switch 80 will again be closed. Thus it is possible to halt the unwinding of the supply package 2 at a predetermined point in the operations in order that the end of the web 4 may be exposed outside the brusher unit 5 and to enable a new supply package 2 to be put in place with its free end attached to the end of the web 4 of the depleted supply package. This feature obviates the necessity of threading up all of the rolls in the brusher unit 5 when the supply package 2 runs out.

In the operation of the web packaging apparatus 1, a supply package 2 is installed in the carriage 10 supported by the wooden core 8 and the

shaft 9. The free end of the web 4 from the supply package 2 must then be threaded into the intermediate unit such, for example, as the brusher unit 5. This may be accomplished, as indicated above, by temporarily attaching the tail end of the previously treated web 4 to the free end of the web from the new supply package 2 and manually starting the web packaging apparatus 1.

One of the first steps to be performed is to position the roller 63 in contact with the outer periphery of the supply package 2. This re-establishes the operating circuit for the web packaging apparatus 1 by closing the switch 80 and repositioning the shaft 68 and the handle 72 in the relationship illustrated in Fig. 2. With the web packaging apparatus 1 supplied with the fabric web 4 and the brusher unit 5 completely threaded up, it is ready to operate.

The push button switch 81 in the operating circuit of the web packaging apparatus 1 is then operated holding a circuit closed through the contacts 82 across the power lines 83 and 84 of a three wire power source embodying the additional power line 85. This energizes the motor coil 86 which in turn energizes the drive mechanism 32 of the wind-up unit 28, thereby causing the fabric web 4 to be unreeled from the supply package 2, passed through the brusher unit 5, and wound up on the wind-up package 3. At the same time, since the switch 80 is temporarily closed, a circuit is completed by closing the normally open contacts 82 so that the size of the supply package will thereafter control the stopping of the web packaging apparatus at the proper time.

From the above explanation of the operation of the roller 63 and the shaft 68, it will be apparent that as the removal of the web 4 from the supply package 2 causes the latter to diminish in size, the switch 80 will be opened. At this point, the contacts 82 will return to their normally open position and the circuit through the motor coil 86 will be broken, thus halting the drive mechanism 32 of the wind-up 28. As previously explained, the manipulation of the handle 72 and the manual operation of the push button 81 thereafter serves to control the run-out of the supply package 2 to enable a new package to be inserted as before without complete re-threading of the brusher unit 5.

While the web 4 is traveling from the supply package 2 to the wind-up package 3, the guide portion 34 on the feeler element 33 of the mercury switch 35 maintains a constant contact with the edge 6 of the web. As the edge 6 of the web 4 shifts from side to side due to the uneven ends of the supply package 2 being unwound, the guide portion 34 of the feeler element 33 follows. This action shifts the mercury tube (not shown) inside the mercury switch to one of three positions, namely, neutral or no contact, contact left, or contact right, depending on the direction in which the edges 6, 7 of the web 4 are offset in the supply package 2.

As long as the web 4 is running true and there is no offsetting of the edges 6 and 7 in the supply package, the motor 37 is idle and the carriage 10 remains stationary. Whenever the tube in the mercury switch is tilted so as to make contact left, for example, it is apparent that the web is laterally offset to the right and a circuit is completed through the limit switch 56, thereby energizing the coil 87. Should the lateral shifting of the carriage 10 tend for some reason to go too far to the left, the limit switch 56 will be

7
operated by the contact of the cam element 54 with the trip lever 59.

This energization of the coil 37 results in the closing of the normally open contacts 88, 89, and 90, thereby completing the three wire circuit to 15 the motor 37 from the power lines 83, 84, 85. With the closing of the motor circuit, the brake 53 is energized and released to free the rotation 20 of the shaft 38. The rotation of the shaft 38 and the chain 48 and the sprockets 43 and 46 10 in the manner above described will cause the carriage 10 to move toward the left in the guides 19.

The carriage 10 will remain shifted to the left until the offset edge 6 of the web 4 starts 15 the drive mechanism to return the carriage toward its neutral position or beyond by reversing the motor 37. The lateral offsetting of the web 4 in the other direction is automatically compensated for in the same fashion, the only difference being in the direction of travel of the carriage. For the reverse operation, the tilting 20 of the mercury switch 35 to make contact right, as for the offsetting of the web 4 to the left, the several normally open contacts 91, 92, 93 will be 25 closed by virtue of the energization of the coil 94 completing the three wire circuit to the reversible motor 37 which, by reason of the reversing 30 feature, will shift the carriage to the right.

While certain representative embodiments and details have been shown for the purpose of illustrating the invention, it will be apparent to those skilled in this art that various changes and modifications may be made therein without departing from the spirit or scope of the 35 invention.

I claim:

1. In a web packaging apparatus, a web let-off and wind-up mechanism for preventing axial offsetting of the web as the package is formed 40 thereon, said mechanism comprising a supply providing a web of substantially continuous length and of uniform lateral dimension; a wind-up for the web; a carriage supporting the web supply; a guide defining a path of travel of the carriage in a direction generally normal to the longitudinal dimension of the web; a drive mechanism for shifting the carriage in the guide; 45 a prime mover for actuating the drive mechanism; a feeler element urged against the edge of that portion of the web extending between the web supply and the wind-up; a make-and-break contact operated by the feeler element for energizing the prime mover; means defining the extremities of the path of travel of the carriage and deenergizing the prime mover whenever the carriage approaches either of said extremities; and means halting the operation of the wind-up when the web supply diminishes to a predetermined minimum but before the supply has run out.

nism: a feeler element urged against the edge of that portion of the web extending between the web supply and the wind-up; a make-and-break contact operated by the feeler element for energizing the prime mover; means defining the extremities of the path of travel of the carriage and deenergizing the prime mover whenever the carriage approaches either of said extremities; and means halting the operation of the wind-up when the web supply diminishes to a predetermined minimum but before the supply has run out.

2. In a web packaging apparatus, a web let-off and wind-up mechanism for preventing axial offsetting of the web as the package is formed thereon, said mechanism comprising a supply providing a web of substantially continuous length and of uniform lateral dimension; a wind-up for the web; a carriage supporting the web supply; a guide defining a path of travel of the carriage in a direction generally normal to the longitudinal dimension of the web; a drive mechanism for shifting the carriage in the guide; 20 a prime mover for actuating the drive mechanism; a feeler element urged against the edge of that portion of the web extending between the web supply and the wind-up; a make-and-break contact operated by the feeler element for energizing the prime mover; a pair of cam surfaces arranged in spaced relation on the guide and defining the extremities of the path of travel of the carriage; means on the carriage actuated by the cam surfaces for deenergizing the prime mover whenever the carriage approaches either 25 extremity; and means actuated by the web supply to halt the operation of the wind-up when the web supply diminishes to a predetermined minimum but before the supply has run out.

CLAUDE A. HOGAN.
